US00D918659S

(12) United States Design Patent (10) Patent No.: US D918,659 S
(45) Date of Patent: * May 11, 2021

(54) CUP

(71) Applicant: SHENZHEN KEAN SILICONE PRODUCT CO., LTD, Shenzhen (CN)

(72) Inventor: Pandian Peng, Shenzhen (CN)

(73) Assignee: SHENZHEN KEAN SILICONE PRODUCT CO., LTD., Shenzhen (CN)

() Term: 15 Years

(21) Appl. No.: 29/701,534

(22) Filed: Aug. 13, 2019

(30) Foreign Application Priority Data

Jun. 21, 2019 (CN) 201930323793.4

(51) LOC (13) Cl. 07-01

(52) U.S. Cl.

USPC D7/523

(58) Field of Classification Search

USPC D7/507, 509, 510, 511, 300.1, 532, 533, D7/529, 523, 624.2, 608, 413, 536, 591, D7/584, 504, 515, 524, 513; D9/452, D9/527, 529, 444, 517, 530, 553, 556, D9/503, 541, 551, 440, 443, 445, 544, D9/520, 571, 501, 502; 220/592.17, 220/592.16, 592.15, 710.5, 758; D24/121, 122, 224, 216; D10/46.2, 46.3

CPC A47G 19/2288; A47G 19/2227; A47G 19/2272; A47G 19/2205; A47G 19/22; A47G 19/03; A47G 23/0216; A47G 23/0258; A47G 23/0241; G01F 19/00

Assistant Examiner — Arva P Adams

(57) CLAIM

The ornamental design for a cup, as shown and described.

DESCRIPTION

FIG. 1 is a front, top perspective view of a cup showing my new design;

FIG. 2 is a front, left, bottom perspective view thereof;

FIG. 3 is a front, right, top perspective view thereof;

FIG. 4 is a front, left, bottom perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

1 Claim, 10 Drawing Sheets
